CONTROL DEVICE FOR GAS BURNERS AND SIMILAR APPARATUS

Floyd J. Bydalek, Milwaukee, Wis., assignor to Baso
Inc., Milwaukee, Wis., a corporation of Wisconsin

Application July 25, 1956, Serial No. 42,379

Term of patent 14 years

(Cl. D52—1)

FIG. 1.

FIG. 2.

FIG. 3.

FIG. 4

Figure 1 is a side elevational view of a control device for gas burners and similar apparatus, showing my new design;

Figure 2 is an end elevation as viewed from the left side of Figure 1;

Figure 3 is an end elevation as viewed from the right side of Figure 1; and

Figure 4 is a top plan view thereof.

The side of the control device opposite the side thereof shown in elevation of Figure 1 is substantially the same in appearance as that shown in Figure 1.

I claim:

The ornamental design for a control device for gas burners and similar apparatus, as shown and described.
